[57] CLAIM

The ornamental design for a safety recapper for hypodermic needles, as shown and described.

DESCRIPTION

FIG. 1 is a top perspective view of a safety recapper for hypodermic needles, showing my new design;

FIG. 2 is a top plan view thereof;

FIG. 3 is a side elevational view thereof, with all other side being identical thereto;

FIG. 4 is a bottom plan view thereof;

FIG. 5 is a cross-sectional view taken along line 5—5 of FIG. 2;

FIG. 6 is a bottom perspective view of a second embodiment of a safety recapper for hypodermic needles, with all side elevational views being identical to that shown in FIG. 3;

FIG. 7 is a bottom plan view of FIG. 6; and

FIG. 8 is a cross-sectional view thereof taken along line 8—8 of FIG. 6.

The broken line showing in FIGS. 3, 5 and 8 is for illustrative purposes only and forms no part of the claimed design.
